UNITED STATES PATENT OFFICE.

FREDERIC E. CHEESMAN, OF BROOKLYN, NEW YORK.

AIR-CHECK DEVICE.

Application filed October 23, 1919. Serial No. 332,591.

To all whom it may concern:

Be it known that I, FREDERIC E. CHEESMAN, a citizen of the United States, residing at Brooklyn, in the county of Kings and State of New York, have invented certain new and useful Improvements in Air-Check Devices, of which the following is a specification, reference being had therein to the accompanying drawing.

10 My invention relates to improvements in air check devices for exposing apparatus for cameras and is in the nature of an improvement upon my U. S. Letters Patent 766,874, wherein the air release for timing the exposure involves the adjustment of concentric tubes, whereas in my present construction I provide a knurled screw which may be conveniently and quickly adjusted by hand and give a very accurate adjustment

20 of air release thereby providing a very desirable adjustment for the exposure.

Referring to said drawings Fig. 1 is a plan view partly broken away and partly in cross-section illustrating an embodiment 25 of my invention. Fig. 2 is a view of the upper part of the same looking from left to right at Fig. 1.

3 indicates the piston chamber into which air is compressed from the bulb 4 in the usual manner beyond the valve 5, the outlet or escape being indicated by the reference

character 6. The air after entering the passage 7 escapes by one or more of the holes 8 which are in the path of the knurled screw 9 so that when the screw is down in the position shown in Fig. 1 a very long exposure is provided for, the air only being able to escape by the lower and more restricted hole, whereas if the screw 9 were lifted say a half inch, the air would escape through all of 40 the holes 8 and the exposure would be considerably shortened.

Of course it will be understood that various modifications may be made in the construction and arrangement of parts without departing from the spirit of the invention as claimed.

I claim:

In an air check device of the class described, an outlet for the air comprising an 50 internally threaded tube provided with a series of holes in one side and a screw adapted to traverse said tube, said holes extending in the direction of the axis of said tube and increasing in diameter in the direction 55 of the head of said screw.

In testimony whereof I hereunto affix my signature in the presence of two witnesses.

FREDERIC E. CHEESMAN.

Witnesses:

ANNA F. DUFFY,
DAVID H. DOUGLASS.
